Hamburg, N.Y. 14075

Filed Oct. 12, 1966, Ser. No. 4,246

Term of patent 14 years

(Cl. D9—199)

FIG. 1.

FIG. 3.

FIG. 4.

FIG. 5.

FIG. 1 is a front perspective view of a container for ice cream or the like showing my new design;

FIG. 2 is a side elevational view thereof;

FIG. 3 is a front end elevational view thereof;

FIG. 4 is a rear end elevational view thereof; and

FIG. 5 is a bottom plan view thereof.

The side not shown is a mirror image of the side shown in FIG. 2.

The circular opening shown in FIG. 5 represents a cavity in the hollow container body.

The conventional bottom cover has been removed for illustrative purposes.

I claim:

The ornamental design for a container for ice cream or the like, substantially as shown and described.
